C. O. WITHERSPOON.

FLUSH TANK VALVE.

FILED JUNE 10, 1920.

UNITED STATES PATENT OFFICE.

CHARLES O. WITHERSPOON, OF MINERVA, OHIO.

FLUSH-TANK VALVE.

Application filed June 10, 1920. Serial No. 387,911.

To all whom it may concern:

Be it known that I, CHARLES O. WITHERSPOON, a citizen of the United States, residing at Minerva, in the county of Stark and State of Ohio, have invented certain new and useful Improvements in Flush-Tank Valves; and I do declare the following to be a full, clear, and exact description of the invention, such as will enable others skilled in the art to which it appertains, to make and use the same.

This invention relates to improvements in flush tank valves of the type which serve to automatically check the flow of water into the tank after the same has been emptied and is being refilled.

The main object of the invention is to provide a device of the above mentioned type which includes a novel valve carrier, the same being equipped with a removable packing which is so connected therewith that it may be quickly and easily replaced whenever necessary or desired by an unskilled hand without removing the body of the device from the tank and without necessitating cutting off of the water.

Another object of the invention is to generally improve upon devices of this class by providing one of extreme simplicity which is effective in operation and is composed of comparatively few, simple and common readily disconnectable parts, which construction makes it possible to install, repair, and replace any parts of the valve very easily and readily, which feature is not true of the types of valves now in use.

A further object of the invention is to provide a practical valve of the type mentioned to take the place of the old-style ball valves, either elevated or of low design, such as are now in common use.

Other objects and advantages of the invention will be apparent during the course of the following description.

In the accompanying drawings forming a part of this specification and in which like numerals are employed to designate like parts throughout the same:

Figure 1 is a side elevation of a valve constructed in accordance with my invention.

Figure 2 is a central vertical sectional view thereof.

Figure 3 is a front end elevation thereof. Figures 4 and 5 are sections taken approximately on the lines 4-4 and 5-5 of Figure 2. Figure 6 is a section taken on the line 6-6 of Fig. 1.

In carrying out my invention I employ a valve body 1 which includes a screw-threaded neck 2, the latter extending through an opening in the tank T and being held in position by means of a retaining nut 3. Extending entirely through the body is a passage 4 which communicates at one end with a suitable water supply pipe (not shown), the outlet end of this passage being downturned and provided with a valve seat 5. Adjacent to and below this valve seat is valve chamber 6 open at its front, the same including a pair of spaced vertical walls 7 and 8, the latter of which is apertured at 9 for communication with the bored enlargement 10 with which a refilling tube 11 connects. Disposed at the top of the body and extending laterally therefrom is a second bored enlargement 12 which constitutes a guide, through which a valve actuating stem 13 extends, the latter having detachable connection at its lower end with a valve 14. At its opposite end it is provided with a head 15 beneath which the forks 16 of bell crank lever 17 are disposed. The bell crank lever in this instance is pivoted between spaced ears 17^a carried by the valve body 1 and is actuated by means of a float controlled rod 18.

The valve 14 may be of any construction. However, I intend to employ the type of valve illustrated. Examination of the same will disclose the fact that this valve includes a shelf-like part 19 which extends into the chamber 6 through its open front, and an enlarged finger grip 20 which is provided with a screw-threaded hole, permitting it to have detachable connection with the reduced screw-threaded end of the stem 13. The part 19 of the valve is provided with a pair of upwardly directed flanges 21, the inner faces of which are inclined downwardly and outwardly in directions opposite to each other so that when the rubber pad 22 is placed between these flanges, it will be held against displacement.

It is to be noted that the head of the actu-

ating stem 13 is slotted to permit it to be rotated, using a screw-driver. Hence, the valve 14 may be quickly and easily removed in order to enable a new packing to be placed thereon.

To remove the renewable rubber packing from the carrier or holder, it is only necessary to insert the end of a screw-driver in the slot in the head of the afore-said stem 10 and turn the screw-driver until the stem becomes disengaged from its carrier. Then, reach down into the tank and grasp the finger-grip or exposed portion of the carrier and slide the latter out of the chamber. When the carrier is removed from the chamber in this way, the worn packing can be removed and a new one substituted therefor and the carrier replaced in its chamber and connected with its stem again for operation. It is to be noted that it is never necessary to remove the valve body from the tank in order to remove the packing, nor is it even necessary to shut off the water, because by opening a couple of faucets in the bathroom and holding down the release lever on the flush tank, the pressure of water coming into the tank is relieved sufficiently to permit the new packing to be installed, and this requires but a few seconds and can be done by 25 unskilled persons as before indicated.

A valve constructed in accordance with this invention will be found extremely advantageous in that it is made up of extremely few inexpensive parts which construction 35 permits it to be easily and readily installed, repaired, or permits any of the parts thereof to be replaced. Particular emphasis is to be laid on the construction of the valve which is removable to permit a new pad or 40 packing to be installed. It is also to be noted that the valve may be adjusted close to or further from the valve seat so as to cause it to close when the water is at a low or high level in the tank, as the case may 45 be.

Careful consideration of the foregoing description in connection with the accompanying drawings will enable persons skilled in this art to acquire a sufficient understanding 50 of the operation and construction as may be necessary for making and using the same. For this reason, further description is deemed unnecessary.

It is to be understood that the form of my 55 invention herein shown and described is to be taken as a preferred example of the same, and that various minor changes in the shape, size, and arrangement of parts may be resorted to without departing from the spirit 60 of the invention or the scope of the subjoined claims.

I claim:

1. A flush-tank valve comprising a body having a water passage therethrough and a 65 valve seat at one end of said passage, below

which is a chamber including spaced vertical walls, a valve vertically movable between said walls, a portion of said valve extending beyond the front vertical edges of the wall and constituting a finger-grip, said finger-grip being provided with a screw-threaded hole, a guide carried by the aforesaid body, being disposed in vertical alinement with said hole, a stem extending through said guide and having its lower threaded end engaged 70 with the threads in the aforesaid hole, and float-controlled means associated with the upper end of said stem for imparting movement to the latter.

2. A flush-tank valve comprising a body 80 having a water passage therethrough at the discharging end of which is a valve seat, said body being provided below said seat with a chamber which is open at its front and bottom and includes closed vertical sides having flat inner faces, a valve removably arranged in said chamber and vertically movable between the inner faces of said sides, a portion of said valve being arranged in the chamber and a portion thereof extending beyond the front edges of said sides and this extended portion constituting a finger-grip, and float-controlled mechanism associated with the finger-grip for automatically actuating said valve. 95

3. A flush tank valve comprising a body having a water passage extending therethrough, at the discharge end of which is a valve seat, said body also embodying a chamber disposed beneath said seat and being 100 open at its front and bottom and including spaced vertical walls, a guide on said body, a float-actuated valve-controlling stem extending through said guide, being equipped on its upper end with an enlargement constituting a head designed to permit a tool 105 to be engaged therewith for rotating said stem, a valve detachably and adjustably connected to the lower end of said stem and extending laterally therefrom through the 110 open front face of said chamber and into the latter, and a renewable packing member carried by the valve and engaged with the aforesaid seat.

4. A flush-tank valve comprising a body 115 for permanent disposition in the tank, said body being provided with a water passage and having a valve-seat at the discharge end of said passage, a chamber beneath said valve, being open at its front and at its bottom, spaced ears on the upper portion of said body and an integral guide, a valve stem slidable through said guide, being equipped on its upper end with a slotted head, and being screw-threaded at its lower end, a 120 forked bell crank lever fulcrumed between the aforesaid ears and having its arms straddling the stem beneath said head, float-controlled means connected with said lever, a 125 valve detachably connected with the lower 130

threaded end of said stem, extending laterally from the latter through the open sides of said chamber and into the latter, a portion of said valve being extended outwardly beyond the chamber and constituting a finger-grip to permit the valve to be slid from the chamber when disconnected

from said stem, and a renewable packing member detachably connected with that portion of the valve extending into said chamber.

In testimony whereof I have hereunto set my hand.

CHARLES O. WITHERSPOON.
